UNITED STATES PATENT OFFICE.

JACOB A. MOSER, OF BERNE, INDIANA.

TENSION-REEL FOR CABLES.

No. 888,639.

Specification of Letters Patent. Patented May 26, 1908.

Application filed February 3, 1908. Serial No. 413,995.

To all whom it may concern:

Be it known that I, JACOB A. MOSER, a citizen of the United States, residing at Berne, in the county of Adams, in the State of Indiana, have invented certain new and useful Improvements in Tension-Reels for Cables; and I do hereby declare that the following is a full, clear, and exact description of the invention which will enable others skilled in the art to which it appertains to make and use the same, reference being had to the accompanying drawings, which form part of this specification.

My invention relates to improvements in tension reels for cables, designed to be employed upon pneumatic straw stackers, and particularly of that class illustrated by my patent of March 10, 1903, numbered 722,451.

The object of my present invention is to provide an improved and simplified means for laterally shifting the hood of a pneumatic straw stacker by imparting to the same at pleasure a rotary movement in either direction, so constructed as to keep the cables taut at all times in use.

My invention consists of a pair of winding drums each containing a helical spring by means of which each drum is operatively connected with its respective shaft; means for operating the said drums independently of each other and of their respective shafts and means for preventing the rotation of the drums in more than one direction in use.

The novel feature of my invention resides in the construction and coöperation of the rope-winding drums and their operative means.

Similar reference numerals indicate like parts in the several views in which

Figure 1 is a side elevation of my invention. Fig. 2 is a side view of the same taken at right angles to Fig. 1 showing the relative arrangement of the coacting parts. Fig. 3 is a detail of one of the rope winding drums with its operating handle in position thereon, the same being in vertical central section to show the arrangement of the contained helical spring and the ratchet mechanism. Fig. 4 is an enlarged detail of the ratchet mechanism in position on the inner face of one of the drum heads.

The winding-drums 1 and 2 identical in construction of common form and proper dimensions are preferably formed of two sections 3 and 4, the latter consisting of an outer head having a fixed or integral perim-

eter 5 upon its inner face, Fig. 3, and a detachable inner head secured thereto in any proper manner. These heads of these drums 1 and 2 are centrally apertured to loosely receive the respective shafts 6 and 7 to the outer ends of which the opposite ends of the bracket 8 are rigidly fixed. This bracket 8 has a centrally arranged concavo-convex strip 9 on its outer face to fit the adjacent side of the stacking tube to which it is secured when in position for use in a well understood manner, and also has a right-angularly arranged integral brace 10 whose outer end is firmly secured to the parallel companion bracket 11 by the bolts 12. These hollow drums are divided into two compartments by means of the sheet metal partition 13 in parallel arrangement with the drum heads, and having a central opening for the shaft. In one of these compartments is arranged the helical spring 14 coiled about the respective shaft, one end of the spring being secured to the said shaft and the other end to the adjacent drum-head in any suitable manner, as by means of a pin 15 whose other end is fixed in the partition 13. The other compartment contains the ratchet mechanism described as follows: A sleeve 16 is loosely mounted on the inner end of the shaft 6, Fig. 3, and is provided with a fixed or integral head or cylindrical enlargement 17 having a peripheral flange 18 and a ratchet wheel 19 upon the inner end thereof adapted to be arranged within the ratchet mechanism chamber. A pawl 20 is pivotally mounted upon the inner face of the drum-head 4 and is adapted for a holding engagement with the wheel 19, as shown in Fig. 4, and is firmly held to its engagement by the spring 21, or other proper means. This pawl is limited in its movement in the other direction by the pin 22 fixed in the inner face of the head 4.

A suitable operating crank handle 23, preferably having a pair of handles, is rigidly fixed upon the outer end of the sleeve 16 which is loosely mounted in a suitable bearing in the upper apertured end of the bracket 11.

The shaft, sleeve and ratchet mechanism of the other drum 2 are in all respects of similar construction except that the head 17 and the sleeve 16 are somewhat extended to avoid any interference of the crank-handles of the two drums, when in operation.

The operation and manner of employing

my invention thus described is obvious and briefly stated is as follows: The hood shifting ropes, not shown, have their inner ends fixed to the perimeter of the respective drums 1 and 2, the said drums having been previously rotated on their respective shafts by hand until the contained coiled springs are adjusted to the proper or desired tension. The adjacent ends of the said ropes are then wound upon the respective drums until all the slack thereof is taken up after which their ends are secured as above stated. It is obvious that when the said hood shifting ropes, fully shown and described in the above mentioned patent, are thus wound upon the drums they cannot rotate under the influence of their contained spring, because they are held from rotating rearwardly by the said ropes as described, and are prevented from rotating forwardly by the tension of the said springs.

When the operator desires to shift the stacker hood to the right he operates the upper crank to the right thereby winding up the operating cable thereon. This he does by rotating the sleeve 16 since the drum 1 is rigidly mounted thereon. When he desires to shift the hood in the opposite direction he rotates the lower drum 2 in the opposite direction by means of its crank handle thereby winding up the cable thereon. My arrangement of spring drums thus keeps the cables taut at all times, and can be operated by hand to a certain limit without any readjustment of the contained springs or surmounted ropes.

Having thus described my invention and the manner of employing the same what I desire to secure by Letters Patent is:

1. In a tension reel for cables a bracket,

having a horizontal shaft fixed in each end thereof, a pair of cable-winding drums loosely mounted on the said shafts respectively, and connected thereto by helical springs coiled about the same; sleeves loosely mounted upon one end of the said shafts having a fixed operating handle upon one end thereof, and a ratchet wheel upon the other end; and a pivoted pawl with each drum adapted to holdingly engage the said wheel to prevent rotation of the said drums in but one direction.

2. In a cable reel a supporting bracket carrying a pair of fixed shafts in horizontal arrangement; winding-drums loosely mounted on the respective shafts; sleeves loosely mounted on the said shafts having a fixed handle upon one end thereof, and a ratchet wheel upon their other end; helical springs arranged in the drums and connecting the respective shafts therewith; and means for engaging the said wheel to prevent the rotation of the drums in more than one direction.

3. A cable reel for pneumatic stacking tubes consisting of a pair of winding drums in coöoperative relation upon fixed supports; helical springs within the said drums connecting the same to their supports and adapted to permit the rotation of the drums against the tension thereof; means for actuating the said drums, and ratchet mechanism for preventing their rotation in more than one direction for the purpose described.

Signed by me at Berne, Adams county, State of Indiana, this 30th day of January, A. D. 1908.

JACOB A. MOSER.
